UNITED STATES PATENT OFFICE.

CHARLES F. SIMMS, OF ATTLEBORO, MASSACHUSETTS, ASSIGNOR TO THE WATSON COMPANY, OF ATTLEBORO, MASSACHUSETTS.

DESIGN FOR A SPOON, FORK, OR SIMILAR ARTICLE.

50,042.

Specification for Design.

Patented Dec. 12, 1916.

Application filed September 29, 1916. Serial No. 122,944. Term of patent 14 years.

To all whom it may concern:

Be it known that I, CHARLES F. SIMMS, a citizen of the United States, residing in the city of Attleboro, county of Bristol, and State of Massachusetts, have invented a new, original, and ornamental Design for a Spoon, Fork, or Similar Article, which is illustrated in the accompanying drawing, forming part of this application.

Figure 1 in the drawing is a view of the design in front elevation. Fig. 2 is a view

of the same in rear elevation. 3 is a fragmentary perspective view on the lines A—A and B—B of Fig. 1.

I claim:

The ornamental design for a spoon, fork or similar article as shown.

CHARLES F. SIMMS.

Witnesses:

PHILIP E. BRADY,
REG. BEUTTEL.
